UNITED STATES PATENT OFFICE.

RANDALL D. GRIFFITH AND CHARLES SCOTT HUNTER, OF DES MOINES, IOWA.

CONDENSER FOR MOTOR-VEHICLE RADIATORS.

Application filed August 27, 1923. Serial No. 659,610.

To all whom it may concern:

Be it known that we, RANDALL D. GRIFFITH and CHARLES SCOTT HUNTER, citizens of the United States, and residents of Des Moines, in the county of Polk and State of Iowa, have invented a certain new and useful Condenser for Motor-Vehicle Radiators, of which the following is a specification.

10 The object of our invention is to provide a condenser for motor vehicle radiators.

More particularly, it is our object to provide a condenser adapted to be mounted on the radiator cap and communicating with 15 the interior of the radiator, which condenser is of simple, durable and inexpensive and effective construction for causing the condensation particularly of alcohol vapors, and causing the liquid of condensation to 20 flow back into the radiator.

With these and other objects in view, our invention consists in the construction, arrangement and combination of the various parts of our device, whereby the objects contemplated are attained, as hereinafter more fully set forth, pointed out in our claims, and illustrated in the accompanying drawings, in which:

Figure 1 shows a front elevation of a 30 radiator cap and condenser embodying our invention.

Figure 2 shows a side elevation of the same.

Figure 3 shows a horizontal, detail, sectional view taken on the line 3—3 of 35 Figure 1.

Figure 4 shows a vertical, sectional view taken on the line 4—4 of Figure 2; and

Figure 5 shows a vertical, sectional view 40 taken on the line 5—5 of Figure 4.

It is well-known that in some types of automobiles, particularly the Ford, the contents of the radiator become very hot and in winter when alcohol is used with water 45 as a non-freezing solution for the radiator, the alcohol vaporizes rapidly and is lost in the form of vapor.

We have provided a condenser of novel structure for receiving the vapor from the 50 radiator, condensing it and causing the liquid of condensation to flow back into the radiator.

Our improved condenser is used in combination with a radiator cap indicated in

the accompanying drawings by the reference 55 character 10.

Our improved condenser comprises a hollow body or member 11 preferably composed of two thin walls 11^a and 11^b of somewhat resilient material.

The walls 11^a and 11^b are secured together at their edges, as at 12, so as to permit slight movement of said walls toward and from each other, except at their point of connection.

In the particular form of our invention herein disclosed, which is shown for the purpose of illustration, we have shown the upper part of the body 11 in the form of 70 a star, having projecting hollow portions A, B and C somewhat like star points.

The lower part of the body 11 is larger and all the parts are so arranged as to drain toward a common point D.

A tube 13 is received in a suitable opening 14 in the upper part of the cap 10 and has a nut 15 screwed on its lower end and an annular shoulder 16 above the cap.

The lower central portion of the body or member 11 is tapered from side to side to the connecting edges except at the common point D, where the member 11 is shaped to snugly receive the tube 13 to which the sides of the member 11 are thus fitted, so that the tube 13 serves to reinforce and 85 strengthen the member 11.

The tube 13 is open at its upper end as at 17, which projects substantially upwardly into the hollow interior of the member 11.

The tube 13 is provided with one or more openings 18 just above the common lower point D, so as to permit free drainage of the liquids of condensation from the member 11 into the lower part of the tube 13.

In the practical use of our improved condenser, the alcohol and steam passes upwardly from the radiator into the cap 10 and through the tube 13.

The greater part of these vapors pass 100 from the upper end 17 of the tube into the member 11 and diffuse through all parts of the member 11 including the projecting points A, B and C.

The member 11 with its projecting hollow portions is subjected to currents of passing cool air, resulting in the condensation of the vapors in the condenser.

All the star points and the lower part of the member 11 are so arranged as to drain toward the common point D, where the liquids pass through the openings 18 and 5 downwardly through the tube 13 to the radiator.

The thin walls of the member 11 and the material and construction thereof are such that if some slight pressure should exist in 10 the member 11, the walls may spread somewhat toward and from each other at their central parts.

The condenser may be made in a variety of forms, either in combination with the 15 cap or as a separate attachment, and it is not our intention to limit ourselves to the particular form of condenser disclosed herein, and it is our purpose to cover by our 20 claims any modified forms of structure or use of mechanical equivalents, which may be reasonably included within the scope of our claims.

We claim as our invention:

1. In a condenser of the class described, 25 a hollow member having projecting hollow portions, adapted to drain to a common point, a tube entering said member at said point and projecting substantially into said

member, open at its inner end and adjacent to said point and serving to reinforce the 30 walls of said member.

2. In a condenser of the class described, a hollow member having projecting hollow portions and comprising spaced resilient 35 walls connected at their edges and capable of some movement toward and from each other except at said edges, adapted to drain to a common point, a tube entering said member at said point and projecting substantially into said member, open at its inner end and adjacent to said point and serving to reinforce the 40 walls of said member.

3. In a condenser of the class described, a hollow member having projecting hollow 45 portions adapted to drain to a common point, a tube entering said member at said point and projecting substantially into said member, open at its inner end and adjacent to said point and serving to reinforce the 50 walls of said member, and a radiator cap mounted on said tube, having the tube projected through it.

Des Moines, Iowa, August 22, 1923.

CHARLES SCOTT HUNTER.

RANDALL D. GRIFFITH.
